UNITED STATES PATENT OFFICE.

JOZEF DLUZNIEWSKI, OF ERIE, PENNSYLVANIA.

COMBINATION-WEAPON.

1,330,062.

Specification of Letters Patent. Patented Feb. 10, 1920.

Application filed September 15, 1919. Serial No. 323,804.

To all whom it may concern:

Be it known that I, JOZEF DLUZNIEWSKI, a citizen of Poland, residing at Erie, in the county of Erie and State of Pennsylvania, have invented certain new and useful Improvements in Combination-Weapons, of which the following is a specification.

The primary object of the present invention resides in the provision of a combination weapon in the form of a combined knife and revolver wherein the barrel and chamber of the revolver are carried by the blade, that is pivotally supported on the knife hilt which carries the revolver grip.

15 A further object of the invention is to provide an extensible grip for a device of the type herein set forth that is capable of extension when desired for certain uses and which is capable of being shortened when 20 the device is used as a knife.

With the above and other objects in view, the invention consists in the novel form, combination and arrangement of parts herein fully described and shown in the accompanying drawing, in which like reference characters designate similar parts throughout the several views.

In the drawing,

30 Figure 1 is a side elevational view of a combination weapon constructed in accordance with the present invention,

Fig. 2 is a top plan view thereof,

Fig. 3 is an enlarged fragmentary view with the grip of the revolver shown in section to illustrate the extension block thereof, and

40 Fig. 4 is a broken cross sectional view taken on line IV—IV of Fig. 3 showing the manner of retaining the adjusting screw in position in the grip.

Referring more in detail to the accompanying drawing, there is illustrated a knife embodying a blade 5 pivoted as at 6 to the hilt 7, a revolver being associated therewith 45 with the barrel portion thereof positioned at the upper edge of the blade 5.

The barrel 8 of the revolver is suitably secured to the upper edge of the blade 5 and carries the chamber 9 which is breakable 50 with the barrel 8 on the pivotal connection 6 between the blade and hilt, the chamber 9 coöperating with the hilt portion 7' to be locked therewith when the chamber is closed

as illustrated in Figs. 1 and 2 with the chamber overlying the hilt extension 10. 55

A trigger device 11 is carried by the hilt extension 10 and is inclosed by a guard 12 which is connected at its rear end to an enlarged block 13 constituting a grip for the revolver. As shown more clearly in Figs. 3 60 and 4, the block or grip 13 is provided with a cylindrical socket 14 into which is slidably received an extension plug 15 having an axial threaded opening 16 into which extends, for engagement, a screw 17. The 65 inner end of the screw extends into a socket 18 provided in the end wall of the recess 14 and is provided with a reduced portion 19 into which the inner end of a set screw 20, arranged transversely thereof, is adapted to 70 extend for purposes of retaining the same in position, and at the same time permitting free rotary movement. The outer end of the screw 17 is provided with a key portion 21 for manipulation of said screw whereby 75 the plug 15 may be moved inwardly and outwardly of the socket 14 for purposes of increasing the length of the grip or shortening the same.

From the above detailed description of 80 the device, it is thought that the construction and operation thereof will at once be apparent, it being noted that when the knife is to be used, the plug 15 may be completely moved into the tubular socket 14 in 85 the grip 13 which will permit the free manipulation of the knife when gripped at the hilt 7. When it is desired to use the revolver, if the grip 13 is not of sufficient length to enable a rigid grasping thereof, 90 plug 15 may be moved outwardly of the socket 14 by operation of the screw 17 to permit a longer grip, to insure the accurate use of the revolver.

While the form of the invention herein 95 shown and described, is what is believed to be the preferable embodiment thereof, it is nevertheless to be understood that minor changes may be made in the form, combination and arrangement of parts without departing from the spirit and scope of the invention as claimed.

What is claimed as new is:—

1. A device of the class described comprising a combined sword and revolver, a revolver grip extending below the sword blade 105

and hilt, said grip comprising a socket member, a screw extending axially thereof, and a plug slidable in said socket and adjusted by said screw.

5. A device of the class described comprising a combined sword and revolver, the revolver grip embodying a socketed portion, a

plug slidable in said socket and means carried by one wall of the socket coöperating with said plug whereby when said plug is 10 rotated, the same is caused to move inwardly or outwardly of said socket.

In testimony whereof I affix my signature.

JOZEF DLUZNIEWSKI.
